CLAIM

The ornamental design for a lock box, as shown and described.

DESCRIPTION

FIG. 1 is a front perspective view of a lock box, showing our new design;

FIG. 2 is a front elevational view of FIG. 1;

FIG. 3 is a rear elevational view of FIG. 1;

FIG. 4 is a top plan view of FIG. 1;

FIG. 5 is a bottom plan view of FIG. 1;

FIG. 6 is a right side elevational view of FIG. 1; and,

FIG. 7 is a left side elevational view of FIG. 1.

The broken lines illustrate unclaimed portions of the design and environment and form no part of the claimed design.

1 Claim, 5 Drawing Sheets(56)
